UNITED STATES PATENT OFFICE.

ROBERT JEWETT PABODIE, OF MAYWOOD, ILLINOIS, ASSIGNOR TO THE GRISCOM RUSSELL COMPANY, OF NEW YORK, N. Y., A CORPORATION OF DELAWARE.

SUBCOOLING CONDENSER.

Application filed May 5, 1921. Serial No. 467,010.

The present invention relates to a combined condenser and cooler. The apparatus is adapted to all work in which it is desired to condense vapor and cool the condensate, but is particularly designed for use in connection with oil refining.

Combined condensers and coolers have been built in which the medium to be condensed and cooled is contained in tubes surrounded by the cooling medium. These tubes extend longitudinally the entire length of the apparatus, the vapor entering at one end, being condensed during its passage through the tubes, and the condensate issuing from the other end. The cooling medium is circulated about the tubes in any desired manner. In this type of apparatus the cross section of the tubular passage is constant throughout its entire length. Since the vapor entering the apparatus occupies a much greater volume than a corresponding weight of condensate, the velocity of flow in the upper part of the tubes, that is, in the portion where condensation is taking place, is much higher than the velocity of the condensate at the outlet. This high velocity in the first portion of the length of the tubes gives rise to an appreciable friction head, and consequently a considerable pressure difference between the inlet and outlet of the tubes will be required to maintain a steady flow. If, however, the tubular cross section is increased to such a value as will obviate this undesirable back pressure, such a large amount of tubing is required as to make the cost of the apparatus prohibitively high.

The present invention has for its principal object to provide a combined condenser and sub-cooling apparatus of the above type in which no appreciable back pressure above outlet pressure is generated when the apparatus is in operation.

It is also an object of the invention to provide an apparatus of the above type in which the velocity of flow throughout the tubes may be maintained at any desired value and will be substantially uniform throughout the entire passage, only a small pressure difference being required to maintain this flow.

It is a further object of the invention to provide means in an apparatus of this type for reducing the inlet velocity of the vapor below that ordinarily occurring in such ap-

paratus, and increasing the outlet velocity of the condensate above that usually found.

It is a further object of the invention to provide an apparatus of this type which may be built in any capacity or any length, and at the same time utilize lengths of tubing throughout which are well within the ability of tube mills to produce.

A still further object is to provide an apparatus of the above type of moderate cost and small dimensions which provides a long path for the cooling medium and a long heat transferring period, during which time the entire volume of the cooling medium is brought repeatedly in contact with the tubes.

In accordance with the above objects, I provide an apparatus comprising a tubular passage whose cross section varies along the length of the apparatus, this feature being secured by employing a series of sections, each section a complete unit in itself, and the various sections containing different numbers of tubes. The tubes of the various sections are connected in series and equalizing chambers or compartments are disposed as desired at the joints between sections.

By this arrangement a uniform flow from each chamber to the succeeding group of tubing is provided, even though the individual tubes in the preceding group may have discharged unequal amounts into the equalizing chamber due to the inequalities of condensation in the various tubes or other cause.

I have illustrated and described a preferred embodiment of my invention in the accompanying drawings and specification, it being understood that the details of construction, such as the number of sections in the various units, the methods of connecting the sections, and the like, may be varied.

In the said drawings, Fig. 1 is a longitudinal section of a cooling condenser in accordance with my invention comprising two individual sections; Fig. 2 is a similar view of an apparatus consisting of three sections; Fig. 3 is a similar view of an apparatus of the above type in accordance with my invention showing a modification in the means of connecting two sections.

Referring to the drawings, particularly to Fig. 1, 1 indicates the shell of the upper section, shown here as a cylindrical casting with open ends which are flanged for the purpose of attachment to the other parts of

the apparatus. An opening 4 is provided in the wall of the shell to serve as an outlet for the cooling liquid. 2 indicates the shell of the lower section, very similar to the upper shell 1 but somewhat smaller in diameter. An opening 5 is provided in the wall of the shell 2 near the bottom and serves as an inlet for the cooling liquid. Within these shells is contained the heat transfer-ring means comprising groups of longitudinal tubes 6 for containing the substance to be condensed and cooled and a baffle 7 which forms a tortuous passage 7' for the cooling liquid. Tubes 6 are preferably straight and of thin metal, supported at the ends by tube plates 8, there being fewer tubes in the lower than in the upper shell. A large supporting tube or cylinder 9 serves to hold the tube plates 8 spaced at the proper interval and furnishes a rigid support for the unit. The baffles 7 are provided with holes through which the tubes pass and are preferably supported by means of the tubes and the member 9. The heating element within each shell is constructed as a unit, and the opening at the upper end of each shell is made sufficiently large to permit of bodily withdrawal of the element.

The upper end of the apparatus is provided with a head 10 having an inlet 11 and constituting a chamber for the vapor as it is delivered to the apparatus. This upper head 10, together with the upper tube plate 8, of the top section, is secured rigidly to the shell

1. The tubes extend downwardly and terminate in the lower tube plate of the upper section which constitutes the top of an equalizing chamber 12, the upper tube plate of the lower section forming its bottom. The side walls 13 of the equalizing chamber are preferably cast integral with one of the tube plates. The tubes of the last section open into the outlet chamber 14, which in turn communicates with the exterior of the apparatus through an outlet 15. The side walls 16 of the outlet chamber fit snugly against the interior of the lower end of the shell 2, thus constituting a sliding fit to allow for expansion and contraction of the tubes. Packing is provided at 17 between the walls of the chamber and the shell to prevent the escape of the circulating liquid from the shell.

The space within the shell surrounding the tubes is preferably provided with a helical baffle 7 of the type disclosed in the Patent No. 1,335,506, to R. C. Jones, the baffle being of a low pitch to constitute a long tortuous path for the cooling liquid and bring it into intimate contact with the tubes 6. The cooling liquid is retained by the side walls of the shell, and a packed joint is provided between the sections 1 and 2 to prevent escape of the liquid. Space is provided between the equalizing chamber 12 and the

walls of the shell, the chamber 12 being held and guided for vertical movement due to expansion and contraction of the tubes by supporting members 18 extending between the shell walls and the walls of the chamber. 70

The vapor as it comes from the evaporators or retorts is first admitted to the vapor inlet 11 and enters the tubes 6 of the upper shell, the number of tubes in the upper section being greater than the number in the lower section. The cooling liquid is preferably circulated in a direction opposite to that of the vapor flow and is accordingly admitted to the lower shell through the inlet 5, from whence it is forced in a tortuous path 80 up through the helical passage 7' into the lower shell, through the space at the outside of the equalizing chamber 12, up through the baffle in the upper shell, and thence out through the opening 4. The vapor is largely 85 condensed in the tubes of the upper section and the condensate, together with the vapor still uncondensed, passes into the equalizing chamber 12, from whence it is fed into the tubes of the lower shell. In passing through 90 these tubes the condensate comes into heat-transferring proximity with the cooling medium shortly after it enters the shell, and the condensate is thereby sub-cooled to any predetermined degree, being then discharged 95 into outlet chamber 14 and from thence through outlet 15 to a storage tank or other suitable container.

When the vapor is being condensed in the tubes its volume is reduced greatly, and for that reason the tubular cross section of the lower unit is much less than that of the upper unit for the purpose of maintaining a uniform flow. Where tubes extending the entire length of the apparatus are used, this reduction of volume in the lower portions of the tubing would create a region of lower pressure and cause the vapor to be sucked into the upper ends of the tubes at a high rate, thus generating an appreciable skin 11 friction which acts to retard rather than increase the rapidity of condensation. This reduced pressure in the tubes above the condensate also greatly retards the flow of the condensate from the discharge port of the 110 apparatus. In accordance with my invention I employ a tubular passage of large section in the upper shell and at the same time utilize short lengths of tubing. In this manner the above mentioned velocity increase may be reduced as desired by properly proportioning the number of tubes in the various sections and constructing each section of the proper length.

The modification illustrated in Fig. 2 is 12 similar to that of Fig. 1 except for the number of sections, vapor being admitted to the inlet 11 passing through the three compartments in series, and the condensate being discharged at the outlet 15. The cooling liquid 13

is admitted through the opening 5 in the lower shell 3 and passes up through the passages of the three shells in series, as has been described, and issues from the condenser 5 through the outlet 4. It will be noted that in this modification the number of tubes in the second and third units is the same. This will be the case in an apparatus in which condensation takes place largely in the upper 10 shell and the lower shells are devoted almost exclusively to sub-cooling the condensate. If, however, the apparatus is designed to accomplish the condensation of the vapor not only in the upper section but in one or 15 more succeeding sections, the cross section of the tubular passage will be varied proportionally in those sections where condensation occurs, the number of tubes being the same only in those sections devoted to sub- 20 cooling the condensate.

In Fig. 3 a further modified construction is shown differing from the previously described device in the manner of connection of the various sections. A two-unit apparatus is shown, the construction of each unit being substantially as has been described. In this modification, however, the lower shell is provided with a head 19 having an outlet 20 opening into the passage 21, which passage serves as a means of communication between the equalizing chamber 12 of the upper section and the head 19 of the lower section. The material to be cooled and condensed, after passing through the tubes of the upper section, is collected in the chamber 12, passed through the passage 21 into the chamber 19, from whence it is delivered into the tubes of the lower section and finally discharged into the chamber 14 and conveyed through outlet 15 to a reservoir or other storage receptacle. The cooling medium enters the lower shell 2 through the opening 5, passes up through the helical passage within the shell 2, and from thence passes through the pipe 22 into the shell 1 of the upper section, from where it is forced up through the passage in the shell 1 and out at the opening 4. This construction obviates the necessity of providing a space between the walls of chamber 12 and the shell, since the cooling water is conveyed from one shell to the other through the external pipe 22. Accordingly, all the sections are provided with sliding joints 17, identical with those shown on the lower sections in Figs. 1 and 2. The passage 21 is provided with an expansion joint 23, and the pipe 22 is provided with an expansion joint 24, to compensate for the expansion and contraction of the shells and tubes as they are subjected to varying temperatures.

It is evident that a considerable devia-

tion from the exact form of construction herein disclosed is possible without departing from the spirit of the invention. It is 65 to be understood that such deviation may be made except as limited by the scope of the appended claims.

I claim:

1. In a sub-cooling condenser, a casing 70 comprising a plurality of sections, a longitudinal passage for the vapor and condensate extending through said sections, said passage comprising a group of straight tubes in each of the respective sections, said tubes 75 being attached to the casing at one point only and slidably supported in the casing at one point so as to be free to expand and contract under the influence of temperature change, the cross sectional area of the passage 80 being constant throughout each section but varying in the different sections approximately inversely as the density of the medium being conveyed.

2. In a sub-cooling condenser, a casing 85 comprising a plurality of sections, each including a shell, a group of tubes in parallel constituting a passage for the vapor and condensate in each section, the number of tubes being different in the various sections 90 and the several groups being connected in series, and a baffle in the space surrounding said tubes constituting a tortuous passage for the cooling fluid.

3. In a sub-cooling condenser, comprising 95 a plurality of sections, a longitudinal passage for the vapor and condensate extending through said sections, the cross sectional area of the passage being constant throughout each section but varying in the different sections and decreasing in the direction of the flow, and a tortuous path for the cooling liquid formed by a baffle surrounding said tubes and serving to bring the cooling liquid into intimate contact with said tubes. 100

4. In a sub-cooling condenser, a casing comprising a plurality of sections, a longitudinal passage for the vapor and condensate extending through said sections and whose cross sectional area is constant 110 throughout each section but varies in the different sections and decreases in the direction of the flow, the upper portion of said passage serving to condense the vapor and the lower portion serving to sub-cool the 115 condensate, and a tortuous path for the cooling liquid formed by a baffle surrounding said tubes and serving to bring the cooling liquid into intimate contact with said tubes, the direction of flow of the cooling medium 120 being opposite to that of the vapor and condensate.

In testimony whereof I affix my signature.

ROBERT JEWETT PABODIE.
